COMBINED ELECTRICAL CONNECTER AND
FUSE PLUGPhilip H. Kelley and Richard E. Kelley,
Greenfield, Mass.

Application April 11, 1933, Serial No. 665,521

10 Claims. (Cl. 200—115.5)

This invention relates to improvements in a combined electrical connection and fuse plug of the type that is employed to connect any special piece of electrical apparatus with a source of electrical energy, as for example, a washing machine and the driving motors for other machines. At the present time, when the electric motor, if a washing machine and its wringer, is electrically connected to the wiring of the house circuit, the 5 fuses in the house circuits often blow out, with the result that all of the house circuits are out of use. The blowing of the fuses frequently results, when an extra load is suddenly placed on the wringer; thus requiring an abnormal current to be thrown or to the house circuit fuse, or 10 fuses.

An object of our invention is to obviate and remove this objection by providing a connector, or fuse plug, that can be readily inserted into any 15 ordinary outlet box, for making a direct electrical connection with the piece of apparatus to be operated, and, combined with this connector, or plug, is a fuse plug, which will blow whenever an abnormal load is placed on the single piece of 20 apparatus, as a washing machine and its wringer, for example. This arrangement, therefore, prevents any of the other circuits of the house from being broken.

Broadly considered, our invention comprises 25 two separable and matched shell members of insulating material, having projecting leads, or terminals at one end for insertion into an outlet box, spring-retaining contacts at its opposite end, to receive the attaching plug on the end of the 30 electric cable of the machine to be operated and a threaded metallic fuse socket to receive a fuse plug that is included in the circuit of one of the projecting leads, or terminals, and spring contact, whereby, when the fuse blows, it is only 35 necessary to remove the blown fuse and insert another in its place, with practically no interruption of the operation of the machine and no breaking of the house circuit.

Referring to the drawing:—

Fig. 1 indicates an elevational view of the combined connector and fuse plug, showing at the left, the connecting cable of a machine to be operated, and, at the right, an outlet box and the fuse removed.

Fig. 2 is a top plan view with the fuse plug removed.

Fig. 3 is a vertical sectional view on the line 3—3 of Fig. 4, showing the threaded fuse socket member for receiving the fuse plug, the upper and lower shell pieces of insulation, the threaded

member, and one of the projecting lead terminals and contacts.

Fig. 4 is a bottom plan view of the upper shell member, showing the two extension terminals and the two spring contact-retaining terminals. 60

Fig. 5 is a plan view of the upper surface of the lower shell member, and

Fig. 6 is a detail view of the contact plate, removed from the assembled connection.

Referring to the drawing in detail:— 65

1 designates the upper end 2 the lower shell members of the connector; the upper member is formed with the cone-shaped extension, as shown, with the recess 3 formed therein, in which is placed the threaded metallic fuse socket sleeve 70 4, having the flat, bottom extension portion 5, that is located under the contact, or lead plate 6, shown in Fig. 6. 7 indicates the twisted end portion of the lead plate 6, to which the spring contact-retaining piece 8 is secured, with the rivet 75 9. The lead plate 6 is electrically connected to the bottom, extension portion 5 of the fuse-socket (see Fig. 3), and is formed with the large opening 10, which registers with a similar opening 11, in the extension portion 5 of the fuse socket. Lo- 80 cated above and below the lead plate 6 and extension 5 of the fuse socket, are the washers of insulation, 12 and 13. 14 designates one of the extension lead terminals having the inwardly, extending angular portion 15, which is fixedly se- 85 cured to the bottom extension 5 of the threaded fuse shell casing 4, the lead plate 6, and the upper and lower discs of insulation 12 and 13, by means of the screws post 16, which has a thread- 90 ed connection with the extension lead terminal 14. 17 designates the other through contact, lead extension, terminal, having the curved, or bowed part 18, which is located in the curved groove 19 of the upper shell member 1. This ter- 95 minal is formed with the end portion 20, located in the recess 21, and to which the spring contact 22 is secured with the rivet 23. The two spring contacts, 8 and 22, are located opposite the open- 100 ings, 24 and 25, which match, or register, with the openings 26 and 27 of the lower, or shell base member 2, when assembled. 28, 29, and 30 designate the remaining three recesses in the top shell member 1 and 31, 32, 33 and 34 designate corresponding and matching recesses in the base, or lower, shell member 2. The member 2 is 105 formed with the curved groove 35 to receive the curved portion 18 of the through extension lead contact 17, and 36 and 37 designate openings in the base member 2, which register with corre- 110 sponding openings in the upper shell member 1.

through which the contact lead members 14 and 17 project, when assembled. The base 2 is formed with the angular disposed recess 38, to receive the angular portion 15 of the extension lead terminal contact member 14 and the central recess 39, to receive the lower end of the screw post 16. 38' is a recess to receive the insulation disc 13. 40 indicates a fuse plug for threading into the threaded fuse sleeve 4. 41 indicates the means for securing the upper and lower shell members together.

The wall outlet is indicated at 42 and the cable 43 and attaching plug 44 with the terminals 45, which engage the spring-retaining contacts 8 and 15. 22. The electric current is as follows:—through the lead member 17, cable 43, back through lead plate 6, threaded fuse sleeve 4, fuse plug 40 to the lead extension contact 14. Should the fuse 40 blow out it is only necessary to replace it with 20 a new one and not disturb the house, or other circuits, in any way.

What we claim is:—

1. A combined connector and fuse plug comprising upper and lower recessed members, means 26 for securing them together, the upper member only having an upwardly upper extending portion with a recess therein, a fuse shell in the recess which is formed with a bottom extension and an opening in one side thereof, a lead plate 30 electrically connected to the said bottom extension and extending through the opening of the fuse shell, a spring contact secured to the said lead plate, a lead terminal extending beyond the shell member and electrically connected 35 to the lead plate when the fuse is inserted in the shell, means for insulating the leads from each other, a second extension terminal, and a spring contact secured to the same.

2. A connector and fuse plug therein, comprising 40 two members, means for securing the same together, said members each having co-operating recesses in their corner portions, lead terminals in the recesses projecting from the members for insertion in an outlet socket, a flat lead plate insulated from one of the lead terminals 45 and connected to the fuse shell, a spring contact thereon and located within the members, a second spring contact on the other projecting lead terminal and located within the members, said 50 fuse shell being electrically connected to the flat lead plate and one of the projecting lead terminals when the fuse plug is inserted.

3. A combined connector and fuse plug comprising upper and lower shell members, one of 55 the members having a metallic fuse socket thereon, two terminals projecting from the casting, two terminals located within the shell members, one of which is electrically connected to the metallic fuse socket and the other forming 60 an integral part of one of the said external projecting terminals, and the other external projecting terminal being electrically connected by means of a lead plate to the centrally located terminal of the fuse socket, disk means for insulating the fuse socket from the said one external 65 terminal, and means for securing the fuse socket, the insulating means, one external terminal and one of the said terminals located within the shell members together, said means also electrically 70 connecting the said one external terminal to a fuse plug in the fuse shell which means secures together the said lead plate, the second lead terminal, the insulating means and the fuse shell, a third lead member and spring contact thereon.

4. A combined connector plug and fuse com-

prising in combination, two recessed members, two contact terminals within the recesses of these members, two externally located plug blades, a slotted metallic fuse socket in one of the said members, blade means in the slotted fuse socket 80 for electrically connecting one of the said contact terminals to the metallic fuse shell, means for electrically connecting one of the said plug blades to the centrally located contact terminal with which a fuse plug engages when inserted in the metallic fuse socket, comprising a screw post threaded into the said plug terminal, means for insulating the said plug blade from the metallic fuse socket and from said contact terminal, and means for securing the recessed members together. 85

5. A connector plug comprising two recessed members having matched openings in its opposite ends, plug blades in some of the openings, spring contacts opposite the other openings, a metallic 90 fuse socket with a slotted bottom portion, a lead plate carrying one of the spring contacts and partially located in and extending through the slotted bottom portion and electrically connected to the fuse socket, one of the plug blades being insulated from the fuse socket—and from the lead plate, and means in the said plug blade for securing the same, the lead plate, fuse socket and insulating means together. 95

6. A combined connector and fuse plug, comprising 105 two matched recessed members, a plug lead extending completely through and projecting beyond the connector, a fuse socket in one of said members, a lead plate electrically connected to the fuse socket, a second plug lead also 110 extending beyond the connector, means for insulating the lead plate from the second plug lead, the lead plate being electrically connected to the fuse socket by means of a screw post in the socket connected to the second plug lead. 115

7. A combined connector and fuse plug, comprising 120 two members, a plug lead extending through and projecting beyond the members, a lead plate, a second plug lead extending beyond the members, means for insulating the lead plate from the second plug lead, a fuse socket in one of said members, the lead plate being electrically connected to the fuse socket, and means in the socket for connecting the second plug lead. 125

8. A combined connector and fuse plug comprising 130 a member, plug blades in the member and projecting from the member, a metallic fuse socket in the member, a lead plate electrically connected to the fuse socket, one of the plug blades being insulated from the fuse socket and 135 from the lead plate, means in the plug blade for securing the same to the lead plate, fuse socket, and insulating means together.

9. A combined connector and fuse plug comprising 140 a member, plug blades in the member and projecting from the member, a metallic fuse socket in the member, a lead plate electrically connected to the fuse socket, one of the plug blades being insulated from the fuse socket and from the lead plate, means in the plug blade 145 for securing the same to the lead plate, fuse socket, and insulating means together,—a plate member secured to said member, and spring means for making an electric connection with the plug blades. 145

10. In a combined connector and fuse plug, two members, each having matching recesses therein, two externally extending plug contacts located in and extending from the said recesses at one end of the members, spring contacts 150

cated in the other recesses, a metallic fuse socket in one member, which is formed—with a bottom portion and an opening in its side, a lead plate electrically connected to the metallic fuse socket—
 5 located in said opening and carrying one of the spring contacts, one of the members having a central recess and a transverse recess formed in the central recess, one of the externally extending contacts being bent at its inner end and
 10 located in the transverse recess, a disc of insulation in the central recess and engaging the bent end of said contact for insulating the bent end

from the lead plate, a disc of insulation on the bottom of the fuse socket for insulating the lead plate from the socket, a screw in the fuse socket engaging the disc of insulation that is electrically connected to the bent end of the said externally extending contact, the construction and arrangement being such that when a fuse plug is inserted in the metallic fuse socket it will engage the screw, as described. 80
